LOOPER MECHANISM FOR SEWING MACHINES

Horace F. Gruman, St. Louis, Mo., assignor to Lewis Invisible Stitch Machine Company, St. Louis, Mo., a corporation of Maine

Original application January 31, 1931, Serial No. 512,661. Divided and this application September 19, 1931, Serial No. 563,841

5 Claims. (Cl. 112—200)

This invention relates to new and useful improvements in looper mechanisms for use in connection with stitch forming mechanisms of sewing machines, and constitutes a division of my co-pending application Serial No. 512,661, filed Jan. 31, 1931 for Improvements in sewing machines.

Among the several objects of my invention are to provide a 4-motion looper which is especially adapted for use in connection with a reciprocating needle having its path of travel in a substantially horizontal plane transverse to the line of feed; to provide such a looper mechanism which is capable of application within a tubular work arm of comparatively small cross sectional area; to provide driving connections between an oscillatory needle shaft mounted in the work arm and the looper for imparting backward and forward movement to the latter; to provide driving connections other than the needle shaft and extending lengthwise of the work arm for imparting needle avoiding movements to the looper, and to provide a looper mechanism which is composed of comparatively few parts and is therefore simple and cheap to manufacture.

With these and other objects in view which will more fully appear, the nature of the invention will be more clearly understood by following the description, the appended claims, and the several views illustrated in the accompanying drawings.

In the drawings:—

Figure 1 is a top plan view of a work arm showing the application of my invention therein,

Figure 2 is a detail vertical sectional view showing the bearings for the needle shaft and one gear connection between the shaft and the looper.

Figure 3 is a perspective view of a bracket on which the looper mechanism is mounted,

Figure 4 is a perspective view of the looper carrier,

Figure 5 is a perspective view of the looper and the looper holder,

Figure 6 is a perspective view of the guard plate which retains the looper carrier in its bearing,

Figure 7 is a detail horizontal sectional view showing the means for oscillating the looper carrier from the needle shaft, and

Figure 8 is a detail elevation of a modified form of looper avoiding mechanism.

Like reference numerals designate corresponding parts throughout the several figures of the drawings.

In the accompanying drawings, I have disclosed my invention as mounted within a tubular work

arm 10 of comparatively small cross sectional area. A bracket 11 is mounted within the arm 10 and extends longitudinally thereof. This bracket is removably attached to the bottom 12 of the arm by screws 13, 13 and includes spaced front and rear bearings 14, 15 and an intermediate bearing 16, the rear and intermediate bearings being formed in a post 17 which is integral with the bracket 11 and extends upwardly into the arm 10. Dowel pins 18, 18 which act as centering pins also connect the bottom 12 of the arm and the bracket 11.

Journalized in the bearings above described is an oscillatory needle shaft 19 which of course extends longitudinally of the work arm. The shaft is retained against longitudinal movements relative to the bracket 11 by means of a collar 20 which engages the front bearing 14 and by the hub 21 of a needle arm 22 which is clamped to the shaft on the side of the bearing 16 opposite the bearing 15. The needle arm 22 extends radially from the shaft and thence rearwardly past the right hand side of the bearing post 17, and attached to the free end of the needle arm is a curved needle 23 which oscillates in an arcuate path extending above the shaft 19 and in a vertical plane at right angles to the longitudinal axis of said shaft. Thus the needle 23 oscillates wholly within the confines of the cross sectional area of the work arm 10.

Cooperating with the needle 23 to form a line of Grover and Baker stitches is a 4-motion threaded looper 24 which is rigidly connected, preferably integrally, to a looper holder 25 having beveled side edges 26, 26. A looper carrier 27 is mounted for oscillatory movements in a recessed bearing 28 formed in the post 17, the longitudinal axis of the bearing 28 being in a horizontal plane and in a plane at right angles to the longitudinal axis of the needle shaft 19, and the bearing being located on one side of said shaft. It will also be noted that the longitudinal axis of the bearing 28 is in the vertical plane containing the path of travel of the needle 23. The looper carrier 27 is provided on its outer face with a radially extending groove or guiding channel 29 in which the looper holder 25 is mounted for straight line reciprocatory movements. The looper 24 is disposed above the holder 25 and above the carrier 27 and has its loop taking movement toward the operator or in other words, in a direction opposite the free end of the work arm. When the carrier 27 is oscillated the looper 24 is given its loop taking and loop shedding movements or in other words its forward and back-

ward travel, and when the looper holder 25 is reciprocated in said carrier the looper is given its needle avoiding movements which, as is well known in the art, is necessary to insure the flat setting of the looper thread in the stitches being formed. A guard plate 30 which is removably attached to one face of the bearing post 17 projects slightly beyond the bearing 28 to retain the looper carrier 27 in said bearing.

10 In order to oscillate the looper carrier 27 and thereby impart loop entering and loop shedding movements to the looper 24, I have fixedly mounted a driving bevel gear 31 on the rear end of the needle shaft 19 and have protected said gear from lint and the like by locating said gear in a recess 32 formed in the bearing post 17. The gear 31 is in constant mesh with a driven gear 33 fixed to the inner face of the looper carrier 27 to oscillate the latter upon oscillation of the needle shaft 19. The gear coupling 31, 33 is a 1-to-1 coupling and consequently the looper travel mechanism is timed with the needle travel mechanism whereby the loop taking or loop entering movement of the looper begins simultaneously with the retractile movement of the needle, and the loop shedding movement of the looper begins simultaneously with the penetrating or forward stroke of the needle.

30 In order to impart needle avoiding movements to the looper 24, I have provided a vertical link 34 having its lower end pivotally connected to one end of a lever 35 which extends longitudinally within the work arm 18 on the left side of the needle shaft 19, and is fulcrumed intermediate its ends on a horizontal pivot screw 36 mounted on the bracket 11. The rear end of the lever 35 is provided with an upstanding arm 37 having substantially horizontal arms 38, 39 and forming therebetween a slot 40. A slide block 41 is fulcrumed on a pivot screw 42 fixed to the looper holder 25, and this block 41 is mounted in the slot 40 for sliding movements relative to the arms 38, 39. Thus when the vertical link 34 is oscillated lengthwise, the lever 35 will be correspondingly oscillated, and therefore the looper holder 25 will be raised and lowered along the groove or guiding channel 29 of the looper carrier 27 and thereby imparting needle avoiding movements to the looper. The parts are timed 50 so that the needle avoiding movements of the looper will be imparted at opposite ends of the looper travel. The looper in its forward or loop taking movement passes under the needle and in its backward or loop shedding movement passes over the needle.

55 In the modified construction shown in Figure 3, there is shown a depending rock arm 43 which is rigidly connected to the rock shaft 44 and pivotally connected to the lower end of this rock arm 60 is a rearwardly extending link 45, one end thereof being pivotally connected to the vertical arm 46 of the bell crank lever 47 which is fulcrumed as at 48 to the post 17. The horizontal arm 49 of the bell crank lever is forked for engagement 65 with a slide block 50 fixed to the looper holder 25. Thus upon oscillation of the rock arm 43 the looper holder 25 will be reciprocated vertically for its needle avoiding movements.

70 It is of course to be understood that the details of structure and arrangements of parts may be

variously changed and modified without departing from the spirit and scope of my invention.

I claim:

1. In a sewing machine, the combination with an oscillatory shaft; of a 4-motion looper; and means for operating said looper comprising a looper carrier supported for oscillation about an axis disposed at right angles to the longitudinal axis of the shaft, a looper holder mounted in the carrier for bodily movements therewith and for radial reciprocatory movements relative thereto, driving connections between the shaft and the carrier for imparting loop-taking and loop-shedding movements to the looper, and means separate from the shaft for imparting needle-avoiding movements to the looper. 10

15 15

2. In a sewing machine, the combination with an oscillatory shaft; of a 4-motion looper; and means for operating said looper comprising a fixed casing having a circular bearing, a looper carrier mounted in the bearing of the casing for oscillations about an axis disposed at right angles to the longitudinal axis of the shaft, a looper holder mounted in the carrier for bodily movements therewith and for radial reciprocatory movements relative thereto, driving connections between the shaft and the carrier for imparting loop-taking and loop-shedding movements to the looper, and means separate from the shaft for imparting needle-avoiding movements to the looper. 25

30

3. In a sewing machine, the combination with an oscillatory shaft; of a 4-motion looper; and means for operating said looper comprising a fixed casing having a circular bearing, a looper carrier mounted in the bearing of the casing for oscillations about an axis disposed at right angles to the longitudinal axis of the shaft, a looper holder mounted in the carrier for bodily movements therewith and for radial reciprocatory movements relative thereto, driving connections between the shaft and the carrier for imparting loop-taking and loop-shedding movements to the looper comprising a driving gear fixed to the shaft and a driven gear fixed to the carrier, and means separate from the shaft for imparting needle-avoiding movements to the looper. 35

40

4. In a stitch forming mechanism, the combination of a 4-motion threaded looper, and means for operating said looper comprising an oscillatory carrier, a looper holder mounted in the carrier for bodily movements therewith and for radial reciprocatory movements relative thereto, and separate means for oscillating the carrier and for reciprocating the holder. 50

55

5. In a stitch forming mechanism, the combination of a 4-motion threaded looper, and means for operating said looper comprising a fixed casing having a circular bearing, a looper carrier mounted in the bearing of the casing for oscillations about an axis parallel with the plane of needle reciprocations, said carrier being provided with a radially extending guiding channel, a looper holder mounted in said guiding channel 60 for bodily movements with the carrier and for radial reciprocatory movements relative thereto, and separate means for oscillating the carrier and for reciprocating the holder. 65

HORACE F. GRUMAN. 70
